COMBINED ICE CHEST AND TRAY

Joseph D. Brown, 20 Red Fox Road, Stamford, Conn.
06903, and Robert P. Brown, 76 Burning Tree Road,
Greenwich, Conn. 06830

Filed Jan. 27, 1970, Ser. No. 21,106

Term of patent 14 years

Int. Cl. D7—99

U.S. Cl. D44—1

FIG. 1 is an exploded perspective view of a combined ice chest and tray showing our new design;

FIG. 2 is a fragmentary side elevational view, partly in section; and

FIG. 3 is a fragmentary side elevational view, partly in section, and with the tray member omitted.

We claim:

The ornamental design for a combined ice chest and tray, as shown and described.
